UNITED STATES PATENT OFFICE.

GUILLERMO VENTURINI, OF SANTIAGO, CHILE.

ELECTRIC LAMP.

Application filed January 14, 1925, Serial No. 2,372. Renewed March 16, 1927.

This invention relates to an improved electric lamp, the general object of the invention being to provide means whereby the lamp can be adjusted to different candle powers.

Another object of the invention is to provide the lamp with filaments of different resistances which are all connected with a single conductor and with manually operated means for connecting any filament with the second contact of the lamp.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a longitudinal sectional view through the improved lamp.

Figure 2 is a section on line 2—2 of Figure 1.

Figure 3 is a fragmentary plan view showing the dial for facilitating adjustment of the lamp.

Figure 4 is a section on line 4—4 of Figure 1.

In these views, 1 indicates the glass body of the lamp and 2 the insulation material which is enclosed by the metal shell 3 which is threaded to engage the usual socket member. The glass stem is shown at 4, and this stem supports four sets of arms 5. Each set of arms supports a filament 6 and the filaments have different resistances so that the candle power of the lamp can be varied by passing the current through the different filaments. One end of each filament is connected to a conductor 7 which is connected with the central contact 8 of the lamp and the other end of each filament is connected to a terminal 9. These terminals are carried by a tubular member 10 arranged in the lamp and in which is rotatably mounted a post 11 which has a knob 12 at its upper end so that by turning the knob the post can be rotated in the tubular member. A conductor rod 13 passes through the center of the post and a plurality of spring pressed contacts 14 are arranged in recesses 15

formed in the post with the springs 16 engaging the rod 13. One of these contacts 14 is arranged in the same plane as each terminal 9 so that when the post is rotated the contact will engage the terminal and thus complete the circuit to the filament, the terminal 9 of which is engaged by the contact 14 through the contact, its spring, the rod 13, the knob and the shell. The contacts 14 are arranged a quarter turn from each other and the knob is provided with a dial 17 so that the post can be turned to place the desired filament in the circuit.

From the foregoing it will be seen that any desired filament can be placed in the circuit by turning the knob 12 to the proper position as indicated by the dial. Thus the lamp will give off light of the desired intensity, the drawings showing a lamp which can be made to give light of four different candle powers. It will of course be understood that any desired number of filaments can be arranged in the lamp.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A lamp of the class described comprising a bulb, a stem therein, a plurality of filaments supported by the stem independently of each other, a conductor connecting all the filaments to one contact of the lamp, a tubular member projecting into the bulb and formed therewith, said member being parallel with the stem, a plurality of terminals carried thereby, each terminal being connected with a filament, a post formed of insulating material and rotatably mounted in the tubular member, a rod carried by the post, spring contacts carried by the post and arranged to engage the terminals as the post is rotated, the springs of the contact engaging the rod, said rod being electrically connected with the second contact of the lamp, a handle connected with the post and indicating means for indicating the position of the spring contacts.

In testimony whereof I affix my signature.

GUILLERMO VENTURINI.
